UNITED STATES PATENT OFFICE.

DELBERT W. SAUNDERS, OF MAQUOKETA, IOWA.

WELL-DRILLING MACHINE.

No. 903,889.

Specification of Letters Patent.

Patented Nov. 17, 1908.

Application filed February 29, 1908. Serial No. 418,591.

To all whom it may concern:

Be it known that I, DELBERT W. SAUNDERS, a citizen of the United States, residing at Maquoketa, in the county of Jackson and 5 State of Iowa, have invented a new and useful Well-Drilling Machine, of which the following is a specification.

This invention relates to improvements in well drilling machines, and is an improvement 10 over the well drilling machine shown in Letters-Patent No. 753,319, granted to me on March 1, 1904, for a well drilling machine. In the said Letters-Patent there is a means provided for imparting a step-by-step 15 rotative movement to the drill or bit without danger of twisting the rope or cable which serves to hoist the drill during the operation of the apparatus, the drill rope and windlass being rotatable as a whole on 20 a vertical axis so that the angular position of the cutting edge of the drill may be changed after each stroke.

The structure of the patent also provided 25 means for regulating the downward feed of the drill in accordance with the rapidity of the drilling operation and the character of the ground, the feed decreasing or increasing as the drill met greater or less resistance, thus avoiding a slack drill rope.

30 The present invention is more particularly directed to the means for providing an automatic feed for the drill responsive to the extent of stroke of the drill as the bore progresses. In the said patent this is provided for by an elastic mounting for the 35 drill-carrying portion of the machine so that when the drill had progressed far enough in the bore to reach the limit of the length of the drill rope then effective, the drill, then 40 meeting no resistance, imparted to the drill-carrying structure a shock or jar causing a spring support for the drill-carrying structure to yield, which yielding is ultimately sufficient to operate an escapement mechanism 45 releasing the drill rope to a predetermined extent. By this means the drill was automatically fed into the bore in accordance with the speed with which it worked its way into the earth.

50 By the present invention the use of springs is avoided and the drill-supporting parts are solidly upheld on the frame of the machine instead of being elastically supported as in the said patent. The elasticity

necessary to cause the yielding to the requisite extent to actuate the drill rope feed is provided by the rope which works the walking beam reciprocating the drill. For this purpose an elastic rope, such as Manila rope, is provided, and this rope will stretch, 55 without detriment, to a sufficient extent when subjected to the strain imparted thereto when the drill descends and meets no obstruction until brought up by the resistance of the said rope. The stretching of this rope 60 is found to be sufficient to permit the necessary movement of the drill-supporting carrier to actuate the feed mechanism for the 65 drill rope.

The invention will be best understood by 70 a consideration of the following detail description taken in connection with the accompanying drawings forming a part of this specification, in which drawings—

Figure 1 is a side elevation of a well drilling machine constructed in accordance with the aforesaid Letters-Patent, but modified to the extent necessary for the application of the present invention. Fig. 2 is a similar view with parts omitted, showing the drill-supporting mechanism turned through an 75 arc of 90° from the position shown in Fig. 1.

Referring to the drawings, there is shown a suitable frame 1 supported upon wheels 2. Near one end of the frame is an upright 80 or standard 3 provided with a suitable number of braces 4, only one of which, however, is shown in the drawings. At the top of the standard is pivotally supported a lever or walking beam 5. Suitably mounted in the 85 frame is a lever 6 pivoted at its forward end and at its rear end adapted to be operated by a cam or eccentric 7 fast on a gear wheel 8 mounted on the drive shaft 9, which latter may receive motion in any suitable manner 90 as by an engine either mounted upon the frame or separately provided. The engine is not shown in the drawings since it forms no part of the present invention. The lever 6 carries a pulley 10 around which is passed 95 a rope 11, one end of which is fast to a drum 12 in the frame and the other end of which is secured to a link 13 on the long end of the lever or walking beam 5. The link 13 may be adjusted to or from the pivot pin of the 100 walking beam 5, and for this purpose the walking beam is provided with a number of perforations 14, through any one of which

the supporting pin of the link 13 may be passed.

In front of the post or standard 3 is a frame composed of two side members 15, 15, 5 parallel to each other and spaced apart, and connected top and bottom by U-clips 16, 17. The bottom clip 17 is mounted upon a pivotal support 18 through which passes the drill carrier 19 extending up between the 10 two side members 15 of the drill frame. The lower end of the drill carrier has means for the securing thereto of the drill point 20. In the drawings the drill carrier and drill are shown in the withdrawn position, but it 15 will be understood that in operation the drill and drill carrier are slowly lowered into the earth as the drilling progresses. On one face of each side member 15 is a 20 guide 21, the two guides being joined by a brace 22. These two guides receive the two legs 23 of a pulley support 24, the support being bent laterally in opposite directions and then again parallel to form the legs 23. The support or carriage 24 has journaled 25 therein a pulley 25 over which there extends a rope or cable 26 fast at one end to the upper end of the drill carrier 19, and after being passed over the pulley this rope is extended downward to a windlass 27 mounted 30 in the lower end of the frame supporting the drilling carrier. At one end of this windlass is a gear wheel 28 meshing with a pinion 29 on a shaft 30 having suitable bearings in the lower end of the drill-carrying 35 frame, and on one end of this shaft 30 there is a ratchet-wheel 31 under the control of two oppositely-operating dogs 32 and 33, each of which is provided with a tooth or head movable into and out of the teeth on 40 the ratchet-wheel 31. These two dogs 32 and 33 and the ratchet-wheel controlled thereby are the same as shown in my aforesaid Letters-Patent and, therefore, need no extended description. The dog 33 is under 45 the control at all times of a spring 40, this spring tending to keep the nose of the dog in engagement with the nose of the ratchet wheel. Connected to the dog 33 on the ratchet-wheel side of its pivot is a rod 34 50 extending upward to a guide 35 on one of the side members 15, and thence through another guide 36 and has its free end within the path of the carriage 24. The rod carries a pin 34' arranged to engage under the pawl 55 32 for a purpose that will presently appear. The upper end of the carriage 24 is connected to a link 37 extending upward through a collar 16' on the clip 16, which collar is inclosed by a bracket 38, and the 60 link finally terminates in a yoke 39 pivotally secured to the corresponding and shorter end of the walking beam 5. The bracket 38 and the pivotal support 18 constitutes the end pivots for the frame carrying 65 the drill support and drill rope windlass

so that those parts may be rotated about a longitudinal axis without danger of twisting the drill rope.

Now, let it be assumed that the drill is in operation and has made progress down into the earth and also that the effective length 70 of the rope 26 is sufficient at the particular time being considered. The lever 6 is moved about its pivot, first slowly downward by the action of the cam 7 on the free end of the 75 lever, thus acting on the rope 11 and walking beam 5 to steadily elevate the drill for the requisite distance. The cam 7 then escapes from the end of the lever 6 and the weight of the drill causes it to drop rapidly and deliver a blow at the bottom of the bore. Slowly the drill forces its way into the earth and ultimately further feed is prevented by the engagement of one of the teeth of the ratchet wheel 31 of the corresponding dog 80 then in the path of the teeth of this wheel. The operation continues and the drill is still able to cut because of the stretching of the rope 11, which is preferably a Manila rope and, therefore, will stretch to the requisite 85 extent without harm. The normal play of the carriage 24 is insufficient to bring it in contact with the upper end of the rod 34, but the sudden jar of the drill carrier 19 on the rope 11 will cause the latter to stretch 90 sufficiently to permit the carriage 24 to ultimately come in contact with the upper end of the rod 34 and move the latter to a sufficient extent to release the ratchet-wheel 31 95 from the dog 33, however, at the same time 100 bringing the dog 32 in the path of the teeth of this ratchet-wheel, because the two dogs are connected by a link 41, as in the aforesaid Letters Patent. The parts are so timed in operation that when the ratchet wheel is 105 released from the dog 33 the rope 26 will pay out a distance permitted by the arrangement of the teeth on the ratchet wheel, as fully explained in the aforesaid Letters-Patent. This extra amount of the rope 26 110 permits the drill to again come in contact with the bottom of the bore and, so the carriage 24 no longer travels sufficiently to come in contact with the upper end of the rod 34 and the rope 11 is relieved from the extra 115 strain due to the fall of the drill carrier 19. The spring 40 lifts the dog 33 into the path of the teeth of the ratchet-wheel and at the same time elevates the rod 34, and the pin 34' on the latter lifts the pawl 32 out of the 120 path of the ratchet-wheel. The drilling now proceeds as before until the effective length of the rope 26 is no longer sufficient to permit the drill point to reach the bottom of the bore. Again the unresisted drop of the drill 125 carrier 19 acts on the rope 11 to stretch it, thus permitting the carriage 24 to once more engage the end of the rod 34 and actuate the escapement dogs 32 and 33 to permit the feeding of the rope 26 as before described. 130

The drilling thus proceeds with the feed automatic so long as desired.

What is claimed is:—

1. In a well drilling machine, a drill carrier, a supporting rope therefor, escapement means for feeding said rope, a reciprocating carriage carrying said rope and supporting the drill point through the intermediary of said rope, an operating means for the escapement in the path of the carriage when abnormally moved in one direction, and a yielding means for reciprocating said carriage and permitting the abnormal movement thereof when the drill point is unsupported.
2. In a gravity drilling apparatus, a drill movable in the active direction by gravity, means for lifting the drill against the action of gravity, a drill rope for the drill, and feeding means for the drill rope actuated by the yielding of the drill lifting means due to the strain exerted on said lifting means for the drill caused by the falling drill.
3. In a gravity drilling machine, a drill moved in the active direction by gravity, means for lifting the drill against the action of gravity, and yieldable to a force greater than the weight of the drill, a drill rope, means for feeding the drill rope step-by-

step, and means whereby an abnormal movement of the drill due to the action of the unresisted fall of the latter on the lifting means, actuates the feeding means.

4. In a gravity drilling apparatus, a drill moving in the active direction under the action of gravity, a drill rope carrying the drill, a sliding carriage provided with a sheave or pulley over which the drill rope passes, a walking beam or lever connected to and actuating the carriage, a rope yieldable under abnormal strains and connected to the walking beam, means acting on said rope for moving the walking beam in a direction to elevate the drill, a step-by-step escapement for the drill rope, and a sliding rod connected to said escapement and having one end in the path of the carriage and engaged by the latter when the carriage is moved abnormally by the fall of the drill when unsupported.

In testimony that I claim the foregoing as my own, I have hereto affixed my signature in the presence of two witnesses.

DELBERT W. SAUNDERS.
